UNITED STATES PATENT OFFICE

2,462,214

ROTARY PUMP WITH EASILY REMOVABLE ROTOR

Carl A. Namur, Kenosha, Wis., assignor to Specialty Brass Company, Incorporated, Kenosha, Wis., a corporation of Wisconsin

Substituted for abandoned application Serial No. 373,358, January 6, 1941. This application June 7, 1945, Serial No. 598,059

5 Claims. (Cl. 103—205)

1

This invention relates to a pump, and more particularly to a pump of the rotary type. The improved pump is especially well adapted for handling milk or other liquid food products, but may be used to advantage in many other applications. The present application is a substitute application for my prior application Serial No. 373,358, filed January 6, 1941, now abandoned.

An object of the invention is to provide a pump of the rotary type in which the parts are in accurate relation and alignment and which at the same time permits of easy and convenient dismantling and reassembly for cleaning. Another object is to provide a pump which will accommodate substantial liquid pressures without leakage and without the additional wear usually associated with higher pressures. Another object is to provide a pump of the rotary type in which the cylindrical surface swept by the impelling means is not interrupted by inlet and outlet ports, thus to produce a more uniform flow of liquid throughout the pumping cycle and avoid irregular wear of the surfaces. Another object is to provide in a pump of this character improved impeller mechanism employing a spacing member for keeping the impeller blades always in proper position with respect to the surface being swept. Still another object is to provide impeller mechanism employing resilient spacing means for the blades, thus to compensate for wear on the various parts. A further object is to provide a rotary type pump which is more efficient and which is sturdy and positive in its operation. Still other objects and advantages will appear after the following description in which one embodiment of the invention is described in detail.

In the accompanying drawings, Figure 1 is a longitudinal vertical sectional view of one form of the improved pump fully assembled; Fig. 2, an elevational view showing the outboard end of the pump; Fig. 3, a view as in Fig. 2 but with the clamp, outboard head of the casing, and pulley removed; Fig. 4, a horizontal sectional view taken as indicated at line 4—4 of Fig. 3 and showing the outboard head in place; Fig. 5, a detail perspective view of the spacer element; and Fig. 6, a detail view showing the shaft nut and rotor retaining nut assembly at the end of the drive shaft, the view being taken as seen from line 6—6 of Fig. 1.

As illustrated, A designates a frame; B, a casing structure providing the liquid enclosure; C, liquid impelling mechanism within the enclosure; and D, mechanism for driving the impelling mechanism C.

The frame A may be of any suitable construction and, as here shown, includes a base 10 and an outer shell 11 into which is received the inner shell 12 which carries the ball bearings 13 and 14. The outer shell 11 is formed at its inboard

2

end to provide the annular bracket 15 into which the casing B is fitted.

The casing B comprises the inboard head 16 and the outboard head 17. The inboard head 16 has a cylindrical wall portion 18 and a rear end portion 19, the outer periphery being cut away at 20 to provide a seat against the bracket 15. A pin 21 in bracket 15 engages a socket 22 in head 16 to hold the head in the correct angular position.

The outboard head 17 has near its outer edge a chamfer corner 23, and the rim 24 of the inboard head portion 18 extends into this chamfer. The edge 25 of rim 24 is beveled so as to provide an annular space for the gasket 26. The gasket 26 is triangular in cross section, and increased pressure from within the casing tends only to press it more firmly into the converging walls retaining it, thus to provide a tighter seal between the inboard and outboard heads.

A clamp 55 extends about the casing and has its ends hooked over the bracket 15. At the center of this clamp is a screw 56 which when turned down presses against the center of the outboard head 17, thus at the same time holding the casing within bracket 15 and holding the heads of the casing together in sealed engagement.

A wear ring 27 is contained within the inboard head 16, and the interior cylindrical surface 28 of this ring is the surface swept by the impelling mechanism in the operation of the pump. Wear ring 27 has its inboard end abutting the end portion 19 of the inboard head and has its outboard end abutting the outboard head 17. Ring 27 is slightly longer than the interior of wall 18, so that as the outboard head 17 is pressed inwardly, this ring is held tight and secure against rotation within the casing. At the same time, the resilient gasket 26 provides an adequate seal between the two heads.

As shown more clearly in Figs. 3 and 4, the casing structure B is provided with inlet and outlet ports. The interior of tube 30 communicates with the channel 31 in head portion 18 outward of wear ring 27. Channel 31 extends into the end-pass channel 32 about the inboard end of ring 27 and also into the channel 33 about the outboard end of ring 27. Thus, when tube 30 is used as a liquid inlet, the incoming liquid passes into channel 31 and simultaneously through channels 32 and 33 into the interior of the wear ring 27.

Similarly, the interior of tube 35 communicates with the channel 36 in the wall 18, and this channel connects with channels 37 and 38 extending respectively around the inboard and outboard ends of the wear ring.

Tube 30 may be the inlet and tube 35 the outlet, or tube 35 may be the inlet and tube 30 the

outlet, depending on which direction the impeller mechanism is rotated.

The impeller mechanism C includes an annular rotor element 40 which is carried on the rotor back plate 41. Element 40 has a cylindrical outer surface and contains a center cavity 43 having preferably a cylindrical surface 44 coaxial with the outer surface. Rotor 40 is mounted for rotation within wear ring 27 and is eccentric with respect to the axis of ring 27 so that at one point its outer surface approaches the surface of the wear ring but near a diametrically opposite point these surfaces are a maximum distance apart.

A plurality of slots 41* extend radially through rotor 40; in the embodiment shown, four such slots are employed, but more or less may be used as desired. Rotor blades 42 extend through the slots 41*, their outer ends engaging the surface 28 of wear ring 27, and their inner ends extending into the hollow center of rotor 40.

A spacer 50 is disposed within cavity 43 and its surface engages the inner ends of each of the blades 42 so as to maintain these blades in their proper positions, with the outer ends contacting the wear ring. This spacer is cylindrical and is unattached to any part. Its axis is preferably the same as the axis of the wear ring 27. It may be a solid cylindrical piece or it may be tubular. However, it should preferably have a resilient surface, and in the embodiment shown it takes the form of a split ring, the ring being expansible so that as the surface of wear ring 27 or the ends of the blades 42 become worn, the spacer ring expands to yet maintain the blades in proper contact with the wear ring surface. If desired, the spacer 50 may be provided with a reinforcing core member.

The driving mechanism D includes the hollow shaft 60 which is carried for rotation in the roller bearings 13 and 14. The driving end of this shaft extends through wall 19 of the casing B and is adapted to receive the hub 46 of the rotor 40. This hub preferably has a slight taper so that as it is drawn into the end of the shaft, a tight accurate fit is effected. At one side, the hub 46 has a channel 47 which is traversed by the pin 61 as the hub enters the shaft. Attached to the hub 46 is a rotor rod 62 which may be secured by having its end screwed into a tapped hole in the end of the hub. The rotor rod 62 extends through the hollow of shaft 60 and has its extended end threaded and engaged by the rotor retaining nut 63 which bears against the end of the shaft. The hub 46 has a taper at the point where it meets the shaft which has a similar taper, these tapered surfaces helping to center the hub and rotor back plate 41.

A drive pulley 65 is mounted on shaft 60 and secured to the shaft suitably by means of the key 66, and a pulley lock nut 67 is screwed on the end of the shaft. The nut 67 is provided with a flange 68, and the rotor retaining nut 63 is equipped with the ears 69 which extend about this flange. With nut 63 so engaged, it is held from movement axially of the shaft.

An efficient liquid seal is maintained between the casing plate 19 and the rotating elements so as to prevent leakage of liquid between intermoving surfaces. This sealing means includes the retaining ring 70, the resilient ring 71, the ring bearing 72, and the resilient ring 73. The construction and operation of such sealing means is described in detail in my copending application, Serial No. 226,999, filed August 26, 1938 now abandoned. It is sufficient to state here that the greater is the pressure of the liquid, the

greater is the efficiency of the seal for shutting off possible leakage from the casing.

In operation, the pump is driven by power applied at pulley 65. The shaft 60 in turn drives the rotor 40, and the space 80, between the rotor and the wear ring, is caused to move about the casing from inlet port to outlet port. The blades also move along with the rotor member and sweep the liquid in front of them. As the blades 10 rotate, the spacer 50 moves along with them, and it also permits movement of the blades with respect to itself. The rounded inner edges of the blades help during such intermovement to maintain constant spacing so that the outer ends of the blades are at all times in the proper contact with the wear ring. When a resilient spacer is used, any wear on either the ends of the blades or on the wear ring or on spacer surfaces is compensated by expansion of the spacer.

When, for example, the rotor is driven clockwise, as seen in Figure 3, the liquid enters the pump through tube 30, passes first into the channel 31, then simultaneously through channels 32 and 33 into the space 80 within the wear ring 27. Upon completion of the stroke, the liquid within the wear ring is forced out simultaneously through channels 37 and 38 into the channel 36 from which it passes out through tube 35. When the rotor is driven in the other direction, the flow is in the opposite direction through the same channels.

By having the entering and leaving liquid pass around the blade-contacting surface instead of through it as in the usual construction, a substantial advantage is gained. In ordinary constructions where the ports break up the blade contacting surface, there is always an unavoidable throttling of the ports by the blades during at least a part of the stroke; and in addition, this break in the surface causes unequal wear, producing pockets in the wearing surface. With the present construction, the blades at all times contact only a uniform unbroken surface, and the inlet and outlet ports are at practically their full opening during the entire pumping cycle.

By having the liquid proceed simultaneously about each end of the wear ring into the pump interior and then simultaneously about each end of the ring on its way out, the liquid pressure 50 on each end of the rotor is substantially the same, and in this way the improved construction eliminates end thrust on the rotor due to liquid pressure.

The improved pump is particularly useful in connection with milk, other liquid foods, and in any application where sanitation is of importance, since this pump is very easily dismantled for cleaning.

To take the pump apart, it is necessary only to 60 loosen and remove the clamp 55 by turning the screw 56 (this loosens the outboard head), and then turn the rotor retaining nut 63 to push the rotor hub 46 from its engagement with the shaft 60. This frees the rotor and also the inboard head and sealing rings. Thus, with two very simple movements, substantially all the essential parts of the pump are loosened and made available for cleaning and inspection or replacement of parts.

Since the engagement of ears 69 on retaining nut 63 prevents movement of this nut axially of the shaft, rotation of this nut can serve only to push the rotor rod 62 endwise, forcing the rotor hub 46 to move directly endwise out of engagement with the shaft 60. Thus, a very closely fit-

ting joint is provided which, with the means provided, can be very simply and easily disengaged.

The reassembly of the parts can be accomplished in reverse order to the dismantling procedure just described. However, it may be pointed out that in securing the rotor to the shaft it is not possible, in a preferred embodiment of the invention, to assemble the parts with the rotor hub in the wrong angular position. The rotor rod 62 is preferably just long enough to extend through the hollow shaft 60 and engage the rotor retaining nut 63 only after the channel 47 on the hub has come into register with the pin 61 of the shaft and the parts have moved axially partly into position. Then turning of the retaining nut 63 draws the hub positively into close fitting relation with the shaft, thus insuring accurate movements of the parts and more efficient operation.

The fact that the wear ring 27 is held positively between the heads of the pump is also an advantage, since this engagement prevents rotation of the wear ring and at the same time the heads are held positively at the same uniform spacing. This enables the rotor to be closely fitted with a minimum of space between the outboard end of the rotor and the outboard head, and no allowance need be made, as in the ordinary constructions, for varying thickness of a gasket.

While in the foregoing description, I have set forth one structure in considerable detail for the purpose of showing an embodiment of the invention, it will be understood that the details of such structure may be varied widely by those skilled in the art without departing from the spirit of my invention.

I claim:

1. In a pump structure providing an impeller chamber, a pump impeller mounted in said chamber and equipped with a rear plate and a hub extending rearwardly from the plate, a hollow shaft for said impeller mounted for rotation within said pump structure and receiving the hub of said impeller plate, means fixed to said shaft for rotating the same, said hollow shaft being provided at its rear end with an outwardly-extending retainer flange, a rod received within said hollow shaft and fixed to said impeller plate hub, said rod having an outer threaded end, a wheel provided with a groove receiving said flange of the hollow shaft and being provided centrally with a nut receiving the threaded end of said rod, and a closure for said chamber axially aligned with said rod.

2. In a pump structure, a hollow shaft rotatably mounted therein, said structure providing an impeller chamber open at its forward end, an impeller within said chamber and provided with an impeller plate having a hub slidably received within the end of said hollow shaft, a key carried by said shaft and engaging a slot extending along said hub and opening at the rear thereof, an impeller rod fixed to the hub of said impeller plate and having a threaded end at its rear, a collar carried by said hub for spacing the same centrally within said hollow shaft, a wheel mounted at the rear end of said pump structure and provided centrally with a nut receiving the threaded end of said rod, interlocking means carried by said wheel and pump structure for rotatably supporting said wheel upon said structure, and a removable closure supported in the forward end of said pump chamber to close the same.

3. In a pump structure providing an impeller

chamber open at its forward end, an impeller in said chamber and provided at its rear with an impeller plate equipped with a rearwardly-extending hub, a hollow shaft rotatably mounted in said pump structure and having its forward end receiving said hub, key and groove means releasably locking said hub and shaft together, a rod fixed to said hub at one end and having its other end threaded, a rotatable wheel equipped centrally with a nut receiving the threaded end of said rod, cooperating means carried by said wheel and pump structure for rotatably confining said wheel upon said structure, and releasable closure means closing the forward end of said chamber in axial alignment with said rod, said wheel when rotated in one direction advancing said rod axially to remove said closure and expose said impeller for cleaning.

4. In a pump structure providing an impeller chamber open at its forward end, an impeller in said chamber and provided at its rear with an impeller plate equipped with a rearwardly-extending hub, a hollow shaft rotatably mounted in said pump structure and having its forward end receiving said hub, key and groove means releasably locking said hub and shaft together, a rod fixed to said hub at one end and having its other end threaded, a rotatable wheel equipped centrally with a nut receiving the threaded end of said rod, cooperating means carried by said wheel and pump structure for rotatably confining said wheel upon said structure, and releasable closure means closing the forward end of said chamber in axial alignment with said rod, said wheel when rotated in one direction advancing said rod axially to remove said closure and expose said impeller for cleaning, and when rotated in the other direction being effective for moving the impeller inwardly within said chamber.

5. In a pump structure providing a chamber open at opposite ends, a hollow shaft rotatably mounted in said structure and extending through one end of said chamber, packing supported about said hollow shaft within said chamber, an impeller mounted in said chamber and provided with an impeller plate closing the space in front of said packing, said plate being provided with a hub received within said hollow shaft, a rod fixed to said hub and extending through and beyond said hollow shaft, said rod being provided with a threaded portion at its rear, a member rotatably secured upon said structure and equipped centrally with a nut receiving the threaded end of said rod, and a closure member movable axially in alignment with said rod and releasably secured upon said pump structure.
